ROAD SIGN

Raymond W. Stacey and Theodore M. Blomquist,
Menlo Park, Calif.

Application June 9, 1941, Serial No. 397,316

2 Claims. (Cl. 40—86)

This invention relates broadly to signs, and more particularly to a sign particularly designed for use on roadways to give to persons using such roadways certain information, such as "Slide ahead"; "One-way road"; "Detour" and the like.

An object of the present invention is to provide a sign of the character which is collapsible so as to be readily stored when not in use and which, when collapsed, is of such a compact form as to be readily carried or transported about to the end that such a sign may be ever handy for use in an emergency.

Further in accordance with the present invention the sign embodies a shiftable web on which a number of signs or legends may be printed or otherwise formed to be selectively brought into position as will best suit the purpose for which the sign is being then used.

The invention together with its objects and advantages will be best understood from a study of the following description taken in connection with the accompanying drawings wherein:

Figure 1 is a front elevational view of the sign set up for use.

Figure 2 is a rear elevational view of the sign set up for use.

Figure 3 is a vertical sectional view of the sign taken substantially on the line 3—3 of Figure 1.

Figure 4 is a vertical sectional view of the sign in completely folded condition.

Figure 5 is a fragmentary view of the sign set up for use, with certain parts shown in elevation, and other parts broken away and shown in section.

Figure 6 is a horizontal sectional view taken substantially on the line 6—6 of Figure 1.

Figure 7 is a fragmentary sectional view taken through a corner portion of the sign and showing the manner of supporting one end of a roller.

Figure 8 is a view somewhat similar to Figure 7 and showing the manner of supporting the opposite end of the roller.

Figure 9 is a perspective view of a bearing plate.

Figure 10 is a fragmentary perspective view of the upper portion of a removable end frame member.

Figure 11 is a perspective view of the body of a roller forming part of the invention.

Referring more in detail to the drawings it will be seen that in accordance with the present invention there is provided a frame indicated generally by the reference numeral 5.

The frame 5 comprises upper and lower tubular members 6 and 7 and vertical end members 8 and 9 that are channel-shaped in cross-section.

The members 8 and 9 are provided in the upper and lower ends thereof with apertures 10 to accommodate screws or other fastening elements 11 through the medium of which the ends of the members 6 and 7 are secured within the ends of the members 8 and 9, thus forming a substantially rectangular frame as shown.

The members 6 and 7 form housings accommodating rollers 12 and 13.

Each of the rollers 12, 13 is adapted to have wound thereon one end of a web or sign strip 14, and which strip is trained through slots 15 provided therefor in the frame members 6 and 7, as shown to advantage in Figure 4.

Also, each roller 13 is mounted within its respective frame members 6, 7, and for rotative movement, through the medium of a pintle 16 that has a threaded tapered shank 17 threaded axially into one end of the body 18 of the roller, and a kerf-equipped head that is accommodated in the aperture provided therefor in a flanged bearing plate 19 secured in one end of the frame member, as shown in Figure 8.

At the opposite end thereof each roller has the body 18 thereof supported through the medium of a substantially tubular pinion 20 forced into an axial socket provided in said end of the body 18 and having an end accommodated in an opening provided therefor in a bearing plate 21 secured in the frame member as shown in Figure 7.

The pinion 20 is secured in position on the body 18 of the roller through the medium of a screw 22 and is provided on its outer end with an integral ratchet wheel 23 with which is engageable a dog 24 secured on the bearing plate 21 to prevent retrograde movement of the roller body.

The pinion 20 of each roller is also provided with a bore 25 of polygonal cross section to accommodate a suitable key or other instrument for use in rotating the roller in a proper direction to bring a selected portion of the strip 14 into view. To this end, the adjacent end member 9 is provided with openings 26 that align with the bores of the pinion 20, as shown in Figure 7.

The respective opposite ends of the strip 14 are secured to the bodies 18 of the respective rollers by having such ends positioned in longitudinal grooves 27 provided in the bodies 18 of the rollers and secured therein through the

medium of wedge or binding strips 29, as shown to advantage in Figure 4.

A supporting board or plate 30 for the strip 14 is secured within the confines of the frame 5 and is provided with a marginal flange 31 and through the medium of which, and suitable fastening elements, the board 30 is secured in the frame.

The board 30, with its marginal flange 31, also provides for the sign a pocket into which is readily foldable a supporting structure for the sign.

The referred to supporting structure comprises a base 32 of skeleton frame structure and provided with feet 33; preferably three feet 33 being employed, and the feet being arranged in triangular formation so as to give a "three-point contact" for uneven surfaces to the end that if the sign should tip sidewise the rear corners of the frame will retard the tipping, thereby supporting the weak side of the base frame.

Pivoted to opposite sides of the base frame 32, as at 34, are supporting standards 35 for the frame 5.

The standards 35 have enlarged ends 35a pivoted to opposite flanges of the backing or supporting plate 30, as at 36, so as to readily fold into the pocket provided by said flanged backing plate 30.

Also at the enlarged ends 35a thereof, the standards 35 are provided with abutment shoulders 37 against which the rear side of the bottom frame member 7 abuts when the device is in extended position for use as shown in Figure 3, whereby to hold the frame 5 in vertical or perpendicular position.

The standards 35 are braced with respect to the frame 32 through the medium of brace rods 38, and the frame 5 is braced with respect to the standards 35 through the medium of pivoted brace rods 39, as clearly shown.

Printed, or otherwise formed on the web 14 are such warning legends as "Slide ahead," "One-way road," "Detour" and the like, and as suggested in Figure 1 and indicated by the reference numeral 40.

Also, each area or section of the strip bearing such a legendary warning is also equipped with an identifying numeral as shown in Figure 1 and indicated by the reference numeral 41.

To assist the operator in bringing the desired section of the strip into position for view, there is mounted on one of the frame members, for example the frame member 8, a plate 42 on

5 which are printed or otherwise formed legends 40a corresponding to the legends on the strip 14, with a corresponding identifying numeral 41a opposite thereto.

Thus, when desired to bring a certain legend 40 to view, the operator, by first glancing at the plate 42, will readily determine the direction in which the rollers 12 and 13 are to be rotated in order to quickly bring the selected section of the web, and the desired warning legend into view.

It will be apparent that when set up for use a rigid sign structure is provided; while, when it is desired to store the frame, the standards 15 35 and braces 38 therefor will readily fold relative to one another and to the frame 32, and the folded elements then readily folded into the pocket formed at the rear of the sign by the flanged backing plate 30.

In Figures 1 and 3, the sign is shown set up for use, and in Figure 4, the sign is shown folded for storage and/or transportation purposes.

It is believed that the many advantages of a sign embodying the features of the present invention will be had by those skilled in the art without further detailed description thereof.

Having thus described the invention what is claimed as new is:

1. In a road sign of the character described, 30 a frame adapted for mounting a double reel and web therein, a supporting base, standards pivoted at one end thereof to the base and at an opposite end thereof to said frame and provided at the last-named end with abutment shoulders 25 against which an adjacent end of said frame abuts when the sign is set up for use, and brace members pivotally connected to said base and said standards.

2. In a road sign of the character described, 40 a frame adapted for mounting a double reel and web therein, a supporting base, standards pivoted at one end thereof to the base and at an opposite end thereof to said frame and provided at the last-named end with abutment shoulders against 45 which an adjacent end of said frame abuts when the sign is set up for use, and brace members pivotally connected to said base and said standards, additional brace members pivotally connected with said standards and said frame, said base member, standards and brace members being foldable into a position within the confines 50 of said frame.

THEODORE M. BLOMQUIST.
